UNITED STATES PATENT OFFICE.

ROBERT ATKINSON MCQUITTY, OF LONDON, ENGLAND.

METHOD OF MANUFACTURING SHEETS OF GELATIN.

1,407,075.

Specification of Letters Patent. Patented Feb. 21, 1922.

No Drawing.

Application filed July 7, 1920. Serial No. 394,539.

To all whom it may concern:

Be it known that I, ROBERT ATKINSON MCQUITTY, a subject of the King of Great Britain and Ireland, residing at 10 Parsons Green, in the county of London, England, have invented a new and useful Improved Method of manufacturing Sheets of Gelatin, (for which I have filed applications in Great Britain, No. 15,465, dated 27 June, 1914; 10 Germany, No. 69,867, dated 29 June, 1920; Belgium, No. 230,776, dated 2 July, 1920; Norway, No. 20,832, dated 28 June, 1920; Sweden, No. 3,883, dated 30 June, 1920; Denmark, No. 27,899, dated 28 June, 1920; 15 Switzerland, No. 129,588, dated 6th August, 1920; France, No. 129,588, dated 2nd July, 1920,) of which the following is a specification.

My invention relates to an improved 20 method of manufacturing thin sheets of edible gelatin and thin or very thin, transparent, coloured or opaque sheets of gelatin such as are used for wrappings for bonbons, for transparent envelopes and for coverings 25 employed in the tops of boxes of confectionery, chocolates and the like.

The usual method employed for the production of edible sheet gelatin is to cut the sheets from a block of gelatin in a semi- 30 plastic condition. A series of sheets are produced simultaneously from the block by means of a frame with a series of taut wires spaced apart according to the thickness of the sheet required. The semi-plastic sheet 35 thus produced is placed to dry and harden upon a wire netting or twine netting support and thus obtains the crinkled appearance familiar to the public in the edible sheet-gelatin of commerce. The thickness of the 40 gelatin thus produced is governed partly by the quantity of the gelatin operated upon and partly by the necessary plastic condition of the sheets when they are placed upon the drying frames and consequently 45 only comparatively thick sheets can be produced.

My invention is designed to provide means whereby thin or very thin gelatin sheets can be manufactured of considerable length and 50 of varying degrees of texture and thickness, colour or opacity without the use of oxgall, paraffin, oil or talc, such sheets being more flexible and less liable to alteration in

colour than those which have hitherto been produced.

According to the method of my invention I employ as a foundation for the thin or very thin gelatin sheets, to be manufactured, a length of material of suitable flexibility adapted to be placed upon a drying wheel; 60 the surface of the said material is glazed, varnished, enamelled or japanned to allow of the sheet of gelatin formed thereon when drying under tension on the curved surface of the wheel, becoming detached and consequently stripped off without the necessity for 65 mechanical stripping means such as a knife.

The gelatin employed to form the film or sheet is dissolved in water. The solution is warmed and spread in an even amount 70 over the surface of the length of flexible material forming the foundation for the gelatin film or sheet. The material is then wound round a drying wheel and remains stationary while being submitted to the 75 action of warm dry air until all the apparent moisture is removed.

After a convenient interval of time (suitably twenty-four hours) the gelatin is 80 stripped in the form of a film or sheet from the glazed face of the strip of material over which it has been spread and wound on to a reel or cut into suitable lengths or dimensions for the purposes for which the sheets are to be employed.

Instead of being wound upon a drying wheel short lengths of flexible material can be hung up in any convenient manner to dry after having been coated with gelatin.

What I claim is:—

1. The method of manufacturing gelatin sheets in which liquid gelatin is first spread over a flexible foundation and said foundation then bent over a curved surface and the film of gelatin dried thereon under tension on said curved surface and finally stripped therefrom without the use of mechanical stripping means.

2. The method of manufacturing gelatin sheets in which liquid gelatin is first spread over a flexible length of material and said material then bent over a drying wheel and the film of gelatin dried thereon under tension on the curved surface of said wheel and finally stripped therefrom without the use of 105 mechanical stripping means.

3. A method of manufacturing gelatin sheets in which liquid gelatin is first spread over a flexible length of glazed material and said material then wound upon a drying wheel and the film of gelatin when under tension on the curved surface of said wheel submitted to the action of warm dry air until the moisture is removed from the gelatin film and which is finally stripped therefrom without the use of mechanical stripping means.

In testimony whereof I have signed my name to this specification.

R. A. McQUITTY.
